UNITED STATES PATENT OFFICE.

THEODORE BURNLEY, OF LONDON, ENGLAND.

SUBMERSIBLE TOY.

1,296,915.

Specification of Letters Patent. Patented Mar. 11, 1919.

Application filed October 15, 1915. Serial No. 56,050.

To all whom it may concern:

Be it known that I, THEODORE BURNLEY, a subject of the King of Great Britain and Ireland, of 101 Gloucester Place, Portman Square, London, England, have invented new and useful Improvements in Submersible Toys, of which the following is a specification.

This invention relates to a submersible toy in the form of a submarine which is actuated by air pressure supplied from an indiarubber ball and tube. When pressure is applied to the ball, air enters the hollow vessel or hull, displacing water which has been previously admitted, and altering its specific gravity, thus causing it to rise. Within the vessel is a tube suitably situated in which a projectile or torpedo is inserted, and this torpedo is expelled by the air pumped in or by means brought into operation by the air.

The invention is illustrated in the accompanying drawings, in which four alternative constructions are shown.

Figure 1 is a sectional side elevation of one modification in which the air is held from escaping prior to discharge by a valve pushed home by the insertion of a projectile. Fig. 2 is a sectional side elevation of another modification in which the inner end of the projectile itself forms the valve, being held in the valve seat like the cork in a "popgun." Fig. 3 is a sectional side elevation of another modification in which the projectile is held by a detent against the valve seat until discharged. Fig. 4 is a sectional side elevation of a further modification operating in a manner similar to that shown in Fig. 3, but differing in constructive details. In each view the torpedo tube is shown loaded.

In Fig. 1 the toy consists of a metal hull A suitably weighted to maintain the same upright and carrying the torpedo tube B B' which is connected by means of tube X and valve Y to the air pressure chamber for which I use an ordinary indiarubber squeeze Z fitted with a non-return valve.

E is a rubber bladder which fits over B and is secured to it at either end.

C is a double acting valve working in a rubber seating C' fitted into the tube B. The valve has a thickened portion at either end which just fits into the rubber sleeve C' and tapers inward to a reduced connection 55 portion. At each end of the valve is a flange to limit the movement.

D is the torpedo or projectile, which on insertion in the tube B pushes back the valve which enters the valve seat with its forward 60 end.

The toy is placed in a pond or tank in which it sinks. On pressure being applied to the ball Z air passes to the tube B and thence through the holes L to the bladder E 65 causing it to expand. As more air passes to it, and the specific gravity of the toy is altered, it rises slowly to the surface of the water. When the pressure in E and B rises to a given point, owing for example to the 70 bladder E being pressed against the hull A, it becomes sufficient to actuate the valve C which opens suddenly, moving forward and allowing sufficient air to pass to expel the projectile, and then closes, the rearward en- 75 larged end entering the sleeve C' under the air pressure as the projectile leaves the tube. The use of the double acting valve C to close the tube B after the torpedo D has been discharged prevents the inrush of water and 80 the sudden sinking of the vessel. The valve may be so arranged that there is a small es- 85 cape through a notch or port hole in the rear end so that the vessel slowly sinks as E de- flates. The bladder E as it is distended may cause a small figure M to rise from a con- ning tower.

In Fig. 2 is shown an alternative construction, in which the projectile D forms a cork which fits in the rubber valve seating C' and is expelled by the increased air pres- 90 sure. A valve C corresponding to the rear- ward half of the valve in Fig. 1 then closes the opening as before.

In Fig. 3 is shown a further construction, 95 in which the torpedo D is held in the tube B by means of a detent F on a lever G, piv- oted at H, which takes into a groove I in the torpedo. On the bladder E being fully in- 100 flated, the free end of the lever G is raised

and the detent F frees the torpedo which is discharged under the air pressure. A valve C serves to cut off the escape of air as before.

5 In a further alternative construction shown in Fig. 4 a float may be provided in the hollow vessel, which prevents the torpedo from being expelled until it drops with the falling water level in the vessel. Here 10 the torpedo is held in the tube by a detent F on a lever G, pivoted at H and having a float P at its free end. As the water level in the vessel drops, the float P sinks and presently frees the torpedo so that, as described with 15 reference to Fig. 3, the torpedo is discharged by the air pressure. In this construction the tube B is supported in the hull A only at its forward end, the inner end being open.

In the constructions shown in Figs. 1-3 20 I use a rubber bladder to contain the air, instead of making the hull itself air tight as shown in Fig. 4; this adds greatly to the stability of the hull, which may be merely clipped together. Holes N are pierced in 25 the hull to allow of the free ingress and egress of the water.

What I claim as my invention is:—

1. A submersible toy comprising a hull having means for the ingress and egress of 30 water, means within the hull for forcing the water out of the hull to permit the toy to rise to the surface, and hand-operated means without the hull for controlling said last mentioned means.

35 2. A submersible toy comprising a hull having ports for the ingress and egress of water, inflatable means within the hull adapted upon inflation to force the water out of the hull to permit the toy to rise to the 40 water's surface, and means external of the hull for distending said inflatable means.

3. A submersible toy comprising a hull having ports for the ingress and egress of water, a bladder within the hull and adapted 45 when inflated to force the water out of the hull to permit the toy to rise to the surface, and a bulb for inflating said bladder.

4. A submersible toy comprising a hull having ports for the ingress and egress of 50 water, a projectile carried thereby, and means for simultaneously firing the projectile and forcing water from the hull to permit the hull to rise to the surface.

5. A submersible toy comprising a hull, 55 means for permitting the ingress and egress of water to the hull, means for forcing air into the hull to force the water therefrom, a projectile carried within said hull and means for firing said projectile when a pre- 60 determined air pressure has been reached.

6. A submersible toy comprising a hull having ports for the ingress and egress of the water, a tube mounted therein, a projectile in said tube, means for forcing air

into the hull to fire the projectile and permit 65 the vessel to rise and valve mechanism in the tube to close the tube when the projectile has been fired.

7. A submersible toy comprising a hull having ports for the ingress and egress of 70 water, a tube mounted therein, a projectile within said tube, a bladder surrounding the tube, means for supplying air to the bladder whereby the projectile is fired and the toy permitted to rise to the surface. 75

8. A submersible toy comprising a hull having ports for the ingress and egress of the water, a tube mounted therein, a projectile in said tube, a bladder surrounding the tube, means for preventing the firing of 80 the toy until a predetermined air pressure has been reached, and means for supplying air to the bladder to fire the projectile and permit the toy to rise. 85

9. A submersible toy comprising a hull 85 having ports for the ingress and egress of water, a tube mounted therein divided into a firing chamber and an air receiving chamber, a projectile within said tube, a bladder surrounding the tube, and means for supplying air to said bladder whereby the projectile is fired and the toy permitted to rise to the surface. 90

10. A submersible toy comprising a hull having ports for the ingress and egress of 95 water, means for forcing water from the hull to permit the hull to rise to the surface and a signal device operated by said means.

11. A submersible toy comprising a hull having ports for the ingress and egress of 100 water, a bladder mounted therein, a signal device on said toy, and means for supplying air to the bladder to operate said device and raise the toy to the surface of the water. 105

12. A submersible toy comprising a hull having ports for the ingress and egress of water, a tube within the hull, a projectile within the tube, means for retaining said projectile within the tube, a bladder surrounding the tube, a signal device operated by distending the bladder and means for supplying air to extend the bladder whereby the signal is operated and the projectile fired. 110

13. A submersible toy comprising a hull 115 having ports for the ingress and egress of water, a tube within said hull, a bladder around the tube, a projectile within the tube, a lever retaining said projectile and adapted to release the projectile upon the distention 120 of the bladder, and means for supplying air to the bladder whereby the projectile is released and fired and the vessel permitted to rise. 125

14. A submersible toy comprising a hull having ports for the ingress and egress of water, a tube within said hull, said tube divided into a firing chamber and an air re-

ceiving chamber, a bladder around the tube, a housed signal device adapted to be operated by the distention of the bladder, means for retaining the projectile until a predetermined pressure has been reached, valve mechanism to close said tube upon firing of the projectile and means for supplying air to

the bladder whereby the signal is operated, the projectile fired, and the vessel permitted to rise to the surface.
